PUMP VALVE

Filed May 25, 1928

UNITED STATES PATENT OFFICE

RAY L. DAVIS, OF WHEELING, WEST VIRGINIA

PUMP VALVE

Application filed May 25, 1928. Serial No. 280,572.

The invention relates to improvements in valves designed primarily for oil well pumps but not necessarily restricted thereto.

The principal object of the invention is to provide a new and improved valve construction which will operate to quickly seat and unseat, will seat with a cushioning effect, will eliminate chattering and leakage, will prevent knock and strain of the pump, will greatly lighten the load and strain on the engine and entire rig, and will eliminate knocking and buckling of suction rods.

Another object of the invention is to provide a construction which will not become clogged with sand, paraffin, etc.

With the foregoing in view, the invention resides in the novel subject matter hereinafter described and claimed, description being accomplished by reference to the accompanying drawings.

Fig. 1 is a vertical sectional view partly broken away and in elevation, showing a pump embodying a standing valve and a traveling valve constructed in accordance with the invention.

Fig. 2 is an enlarged vertical sectional view of the traveling valve.

Figs. 3 and 4 are transverse sectional views on lines 3—3 and 4—4 of Fig. 2.

Fig. 5 is a side elevation partly broken away and in section, of the standing valve.

In the drawing above briefly described, C denotes a well casing, B has reference to the stationary pump barrel, D denotes an anchoring device to which the lower end of said barrel is connected, S refers to the standing valve in the lower portion of the barrel B, W denotes the working barrel, and T designates a traveling valve at the upper end of the barrel W, connected with the pump rod R. T' indicates a second traveling valve at the lower end of the working barrel W, P indicates a portion of packing means carried by the stationary barrel B for engagement with the working barrel W, and F refers to a follower for adjusting the packing P.

The present application is not concerned either with the general construction of the pump, with the packing and its adjusting means, or with the valve T', but resides in a

novel construction for the standing valve S or the traveling valve T, or both. The construction of both of these valves is substantially the same, and hence a description of the traveling valve will, for the most part, suffice for both.

The valve T embodies a cage 6 of unusual length, in that it is much longer than the ordinary cage. The lower portion 7 of this cage is annular for connection with the upper end of the working barrel W, and threaded into this annular portion is a seat ring 8. This seat ring is provided with a seat 9 for a ball valve 10, and with a second seat 11 which surrounds said seat 9. Co-operable with this seat 11, is a cap valve 12 which extends over and around the ball valve 10 and is disposed within the cage 6, to be guided by the latter. The upper end 13 of this cap valve 12, is formed with a fluid passage 14 and with a valve seat 15 therefor, but the side wall 16 of said cap valve is imperforate. A second ball valve 17 is co-operable with the seat 15, and a second cage 18 is provided for this valve, said cage 18 being disposed within the cage 6 and carried by the cap valve 12. Preferably, the upper end 13 of valve 12 is separate from the side wall 16 of said valve and acts as a coupling between this valve and the cage 18, being threaded into both.

The cap valve seat 11 of the valve T is steeply inclined and engages the inner side of the wall 16, said wall being beveled as shown in Fig. 2. The corresponding seat 11' of the standing valve S however, while also steeply inclined, engages the outer side of the valve wall 16, which side is suitably beveled. These differences in construction may be followed if desired, but are not essential. The only other differences between the standing and traveling valves, are that the latter is provided with an appropriate connection 9 for the pump rod R and may if desired be provided with means for connecting it temporarily with the follower F for turning the latter to tighten the packing means P. This means however, forms no part of the present invention and is hence omitted.

By constructing the valves in or substantially in the manner shown and described,

they are exceptionally quick-acting in effecting either a passage of liquid or in trapping off said liquid. The cap valve slides vertically and when it closes, traps off the liquid, permitting positive and quick seating of the contained ball valve with a cushioned effect. The other valve 17 and the passage 14, permit part of the liquid to discharge through this passage at each stroke of the pump. Thus, not only is easy liquid flow provided for, but passage of liquid takes place through the cap valve 16 to continually flush the same and prevent clogging thereof with sand, paraffin, etc.

15 While excellent results are obtainable from the general construction shown and described, it is to be understood that within the scope of the invention as claimed, variations may be made.

20 I claim:—

1. A pump valve comprising a cage having a valve seat and a second seat surrounding the first named seat, a check valve co-operable with said first named seat, a cap valve 25 within said cage extending over and around said check valve and engaging said second seat, the upper end of said cap valve being formed with a fluid passage and a valve seat therefor, and another check valve co-operable with this seat.

2. A pump valve comprising a cage having a ball valve seat and a second seat surrounding said ball valve seat, a ball valve co-operable with said ball valve seat, a cap 35 valve within said cage extending over and around said ball valve and co-operating with said second seat, the upper end of said cap valve having a fluid passage and a ball valve seat therefor, a second ball valve co-operable 40 with the last named valve seat, and a second cage for said second ball valve, said second cage being disposed within the first named cage and carried by said cap valve.

45 In testimony whereof I have hereunto affixed my signature.

RAY L. DAVIS.
